Inventor:

George B. Bosco

UNITED STATES PATENT OFFICE

GEORGE B. BOSCO, OF CHICAGO, ILLINOIS

WALL TIE

Application filed May 2, 1928. Serial No. 274,478.

The main objects of this invention are to provide an improved form of anchoring device for tying a member to a structural unit; to provide an improved anchoring device which is particularly adapted for use as a wall tie or as a concrete insert used in concrete construction work; to provide a device of this kind having an improved form of channel member adapted to be embedded in a concrete unit; and to provide an anchoring device having an improved form of tie adapted to be bent to various angular positions relative to the channel for attachment to different kinds of structural facing units.

Illustrative embodiments of this invention are shown in the accompanying drawing, in which:—

Figure 1 is a perspective of one form of anchoring device particularly adapted for use as a wall tie.

Fig. 2 is a fragmentary horizontal section of a concrete column having anchored thereto another form of wall tie particularly adapted for use in connection with a facing material of terra cotta.

Figure 3 is a fragmentary horizontal section of a concrete column, having attached thereto a device similar to the one shown in Fig. 1, and showing the tie member bent.

Fig. 4 is a fragmentary perspective showing the outer end of the tie bent to form a loop embracing a pipe.

The common type of wall tie heretofore in use included a key made of a flat strip of metal having one end interlocked with a channel member and having its other end adapted to be embedded between the layers of brick or stone in a structural facing unit. Such prior forms of ties were generally satisfactory for use in connection with stone or brick facings because the flat keys could lie flat in the mortar between two layers.

However, in connection with terra cotta facing units, such prior devices were objectionable, mainly due to the fact that the terra cotta units required wall ties capable of being bent, and the flat keys of prior devices could not be bent laterally.

In the construction shown herein, the improved anchoring device comprises an im-

proved form of channel member 1 and a bendable tie member.

The channel member 1 is preferably formed of sheet metal and comprises an arched base part 2 and a pair of sides 3 converging toward an opening 4 extending longitudinally of the channel.

Formed in the arched base part 2, is a plurality of apertures 5 for receiving nails 6 which extend through the opening 4 so as to be adapted to be driven into the form, not shown.

The sides 3 are flared outwardly adjacent the opening 4 to provide flanges 7 adapted to bite into the form, under the pressure of the nails 6, for making a tight joint between the channel and the form to prevent any concrete from entering the opening 4.

In the forms shown in Figs. 2 and 3, the channel member 1 is embedded in a concrete column 8 for use as a wall tie, and the opening 4 is located in the front side of the column for receiving the tie which binds the facing unit, not shown, to the column.

The tie element may be a rod of round or rectangular cross section of a size which will give it the necessary strength and still permit it to be bent to the desired shapes.

In the form shown in Figs. 1 and 3, the tie comprises a rod 9 which is slidable in the opening 4. The inner end of the rod 9 is located within the channel and is bent to form a head or hook 10 having inclined bearing surfaces 11 and 12 adapted to engage the converging sides 3 of the channel to secure the rod against withdrawal.

The breadth of the hook 10 is less than that at the widest part of the channel member so as to permit the hook 10 to be readily turned within the channel when the parts are being interlocked.

The depth of the hook 10 is less than that of the channel so as to allow considerable space at the inner part of the channel in which the hook may be turned.

The outer end of the tie rod 9 is adapted to be embedded in the facing element and its extremity may be bent to form a shoulder 13. The outer end of the tie rod is bendable either transversely or longitudinally relative to the

channel member which permits it to enter the facing unit at any desired point.

In the form shown in Figure 4, the outer end of the tie rod is bent to form a loop 14 for embracing a pipe 15. The rod is provided with apertures 16 for receiving a bolt 17. When the device is used as a pipe hanger, as shown in Fig. 4, the channel member 1 is embedded in the ceiling.

10 In the form shown in Fig. 2, the tie comprises a rod 18 having its inner end bent to provide a hook 19 similar to the hook 10.

The outer end of the rod 18 is bent to form an eyelet 20 to which a plurality of separate 15 tie rods 21 is secured. The tie rods 21 may be attached to various parts of the facing unit.

In operation, the channel member is secured to the temporary form by the nails 6 during the pouring of the concrete. After 20 the concrete has set, the form is removed, leaving the channel embedded in the concrete. The tie is then inserted through the opening 4 and turned so as to bring the shoulders 11 and 12 into engagement with the 25 sides 3.

The outer end of the tie may then be bent to any desired shape for engagement with the other unit.

I claim:

30 An anchoring device comprising a channel member adapted to be embedded in a structural unit and having an opening extending longitudinally thereof, the sides of said channel converging toward said opening, and a 35 bendable tie rod slidable in said opening, the inner end of said rod being located in said channel and being bent to form a bearing head having inclined bearing surfaces adapted to engage said converging sides, one of said 40 bearing surfaces being substantially flat and being formed on the inner extremity of said tie rod, said head being of greater breadth than said opening but of less breadth than said channel, the thickness of said tie rod being 45 less than the width of said opening to permit said head to be turned in said channel, said head being also of less depth than said channel whereby the inner extremity of said head is normally spaced from the base of said 50 channel to permit a limited axial movement of said tie relative to said channel.

Signed at Chicago this 28th day of April, 1928.

GEORGE B. BOSCO.
